UNITED STATES PATENT OFFICE

WILLIAM P. ARON, OF DALLAS, TEXAS, ASSIGNOR OF ONE-HALF TO JOHN E. KNOTT, OF
DALLAS, TEXAS

DESIGN FOR A FAN

Application filed February 20, 1931. Serial No. 38,735. Term of patent 14 years.

To all whom it may concern:

Be it known that I, WILLIAM P. ARON, a citizen of the United States, residing at Dallas, in the county of Dallas and State of Texas, have invented a new, original, and ornamental Design for Fans, of which the following is a specification, reference being had to the accompanying drawing, forming part thereof.

Figure 1 is a side elevational view, and Figure 2 is a front elevational view of a fan, showing my new design.

I claim:

The ornamental design for a fan, as shown.

WILLIAM P. ARON.
